United States Patent Office

Des. 176,272
Patented Dec. 6, 1955

176,272

ELECTRIC VEHICLE

Frank J. Laher, Orinda, Calif.

Application April 4, 1955, Serial No. 35,339

Term of patent 14 years

(Cl. D14—3)

FIGS. 1-6

Figure 1 is a perspective view of an electric vehicle incorporating my new design, looking toward one side thereof; and

Figure 2 is a rear perspective view thereof taken from the other side.

I claim:

The ornamental design for an electric vehicle substantially as shown.
